GARMENT LOOP ATTACHMENT

Gertrude A. C. Baxter, East Orange, N. J.

Application March 24, 1934, Serial No. 717,235
Renewed August 6, 1936

3 Claims. (Cl. 24—85)

This invention relates generally to guide loops for maintaining the position of the shoulder straps attached and designed to hold women's undergarments, such as brassières, slips, chemises, shirts and the like. More specifically, the invention relates to an attachment depending from the undersurface of the seam of a garment whereby a fixed guide is afforded for the aforementioned straps to insure against their displacement off the shoulders of the wearer.

The main object of the invention is provision of structure whereby an attachment is detachably pinned to the material of the undersurface of the seam on the shoulder of a garment, said attachment having a depending tab adapted to be opened and closed for the formation of a loop, the said loop serving as a guide for the shoulder straps of the undergarments.

Another object of the invention is provision of structure whereby a loop guide is provided for the shoulder straps of undergarments, said loop guide giving such straps freedom of play and freedom of displacement at the will of the wearer.

A further object of the invention is provision of structure, simple to operate and economical to manufacture, which does not penetrate and which cannot be detected through the outer surface of the garment wherever attached.

These objects and other incidental ends and advantages of the invention will hereinafter appear in the progress of the disclosure.

The drawing attached hereto shows a preferred embodiment of the invention wherein corresponding reference characters designate corresponding parts throughout the several views.

Figure 1 of the said drawing is a front elevational view of a woman's garment showing the device of the invention attached to the undersurface of a shoulder seam.

Figure 2 is a cross-sectional view of Figure 1 along the line 2—2 thereof.

Figure 3 is an enlarged view of the embodiment of the invention showing the parts thereof in relative and pre-attached position.

In accordance with the invention and in accordance with the accompanying drawing, numerals 10, 11 and 11a represent generally the neck, shoulder and arm portions of the wearer of any garment to which the device is attached. The garment to which the invented device is attached is represented in its parts by numeral 12 as the shoulder portion, numeral 13 as the sleeve portion, numeral 14 as the neck portion and numeral 15 as the body portion.

An undergarment on the wearer, the body of which is designated 17, said 17 representing a slip or chemise or the like, is maintained or supported in position by the set of shoulder straps 18 passing around the shoulders of the wearer. 5 16 represents the ordinary and usual seam connecting the arm portion of a garment to the body portion and to the undersurface of which the embodiment of the invention herein is attached at the upper shoulder portion. 10

The attachment of course may be attached to any seam at the shoulder of the garment and on the undersurface thereof but as shown, is attached to seam 16 of the drawing.

19 shows a portion of the garment cloth adjacent one side of shoulder seam 23, while 20 is the underportion and superfluous part of cloth 19. 21 and 22 oppositely adjacent to seam 23 represent the corresponding parts of 19 and 20. 15 20

The embodiment of the invention proper is now to be described.

Numeral 25 designates a tape portion or ribbon which is provided adjacent the terminal portions thereof with fastening means such that a loop is formed when said fastening means are in articulated position. The fastening means comprise preferably the elements of a snap fastener, element 28 being the male portion thereof, while element 27 is the corresponding female portion. 25 30

Numeral 24 represents a sleeve, preferably metallic, frictionally engaging the intermediate portion of tape or ribbon 25 and having on the upper surface thereof a lumen for the penetration of safety pin 26 therethrough. As is shown in Figure 1, safety pin 26 is attached to the undersurface of seam 23, to wit, through the materials 20 and 22 of the garment cloth. Thereupon the free ends of tape 25 are brought below and under the shoulder straps of the undergarment and fastened together to form the loop hereinbefore mentioned. Such loop assures the maintenance of position of the shoulder straps of the undergarments so long as the seam of the main garment rests above the arm portion of the wearer. 35 40

There are no stiffening elements employed for the effectuation of such object nor are any unsightly expedients employed. 45

In the removal of the overgarment the hand is merely inserted through the upper shoulder portion to detach the loop formed for the straps by unfastening the snap fastener heretofore described. When the garment is to be washed, 50 55

safety pin 26 is merely opened and detached from the seam portion of the garment.

I wish it understood that minor changes and variations in the combination of parts, relative position of parts, integration of parts and material of the several parts may all be resorted to without departing from the spirit of the invention and without departing from the scope of the appended claims.

10 I claim:

1. In a device of the class described, the combination of a fabric-unit, a sleeve frictionally engaging and surrounding said fabric-unit, a safety pin secured to the outer face of said sleeve, and fastening means near the ends of said fabric-unit.

15 2. In a device of the class described, the com-

bination of a flat strip of fabric provided near its ends with snap fasteners, a metallic sleeve frictionally engaging and surrounding said strip of fabric between said snap fasteners, and a safety pin positioned longitudinally of said strip of fabric and secured to the back or outer face of said sleeve.

3. In a device of the class described the combination of a strip of fabric provided with fastening means near its ends whereby when the fastening means are brought together said strip forms a loop, a sleeve frictionally mounted on said strip between its fastening means, and a safety pin mounted on said sleeve at the middle of and extending longitudinally of said strip.

10 15 GERTRUDE A. C. BAXTER.
